UNITED STATES PATENT OFFICE.

WILLIAM PRELLWITZ, OF EASTON, PENNSYLVANIA, ASSIGNOR TO INGER-SOLL-RAND COMPANY, OF NEW YORK, N. Y., A CORPORATION OF NEW JERSEY.

ROLLER-GUIDE FOR CHANNELING-MACHINES.

No. 857,961.

Specification of Letters Patent.

Patented June 25, 1907.

Original application filed November 21, 1906, Serial No. 344,460. Divided and this application filed January 23, 1907.
Serial No. 353,583.

To all whom it may concern:

Be it known that I, WILLIAM PRELLWITZ, a citizen of the United States, and a resident of Easton, in the county of Northampton and State of Pennsylvania, have invented 5 new and useful Improvements in Roller-Guides for Channeling-Machines, of which the following is a specification.

The object of this present invention is to 10 provide certain improvements in the construction, form and arrangement of the several parts of a roller guide whereby the outer guide roller support may be made detachable; in which the inner guide roller is made 15 plain for engaging the rear sides of the drill steels and the outer guide roller is made flanged for engaging the edges and front sides of the said drill steels; in which novel means are employed for oiling the guide 20 rollers and in which novel means are employed for preventing the loss of the locking bolt and key when the outer guide roller support is detached from the inner guide roller support.

25 In the accompanying drawings, Figure 1 represents the roller guide in front elevation, Fig. 2 represents the same in side elevation, Fig. 3 is a vertical section taken in the plane of the line A—A of Fig. 2, looking in the direction of the arrows, Fig. 4 is a transverse vertical section taken in the plane of the line B—B of Fig. 1, looking in the direction of the arrows, Fig. 5 is a horizontal section taken in the plane of the line C—C of Fig. 2, 30 looking in the direction of the arrows, and Fig. 6 is a horizontal section taken in the plane of the line D—D of Fig. 2, looking in the direction of the arrows.

The inner guide roller support is denoted 40 by 1 and the detachable outer guide roller support by 2. The inner plain guide roller is denoted by 3 and the outer flanged guide roller by 4.

The axle 5 for the inner guide roller 3 is 45 secured at its ends within the support 1, and is provided with a longitudinal oil passage 6 extending from end to end therethrough. This oil passage has one or more branch ducts 8, 9, for feeding oil to the bore of the 50 roller 3. Oil chambers 10, 11, are provided in the sides of the support 1, which chambers

are in open communication with the passage 6 in the axle 5. These oil chambers 10, 11, may be filled through holes closed by the screw caps 12, 13. For more effectually and 55 economically feeding oil to the bore of the roller 3, a piece of wicking 7 is passed through the passage 6 and has its ends coiled within the oil chambers 10, 11.

The axle 14 for the outer flanged guide 60 roller 4 is secured at its ends within the detachable support 2 and is provided with a longitudinal oil passage 15 extending from end to end therethrough. This passage 15 is provided with one or more branch ducts 65 17, 18, for feeding oil to the bore of the roller 4.

Oil chambers 19, 20, are provided in the sides of the detachable support 2, which chambers are in open communication with the passage 15 in the axle 14. These oil 70 chambers 19, 20, may be filled through holes closed by the screw caps 21, 22.

For more effectually and economically feeding oil to the bore of the roller 4, a piece of wicking 16 is passed through the passage 75 15 and has its ends coiled within the oil chambers 19, 20.

The axles 5 and 14 are removably secured in position by providing locking bolts 23, 24, for impinging against the ends of the axle 80 5 and locking bolts 25, 26, for impinging against the ends of the axle 14. Screw caps 27, 28, are arranged in alinement with the axle 5 and screw caps 29, 30, are arranged in alinement with the axle 14 so that the said 85 axles may be removed when released by their locking bolts, by a longitudinal movement in either direction.

The means which I have shown for detachably securing the outer guide roller support to the inner support is as follows:—Two locking bolts 31, 32, extend inwardly through the detachable support 2 and are provided at their inner ends with heads 33, 34, arranged to be dropped into enlarged 90 portions 35, 36, of recesses opening through the top of the inner guide support, the reduced portions 37, 38, of said recesses opening through the front of the said inner guide roller support. Shoulders are thus formed 95 100 for holding the bolts against outward movement when their heads have been dropped

into the said enlarged portions of the recesses.

The outer ends of the bolts are provided with elongated slots 39, 40, through which 5 tapered locking keys 41, 42, extend, the inner faces of said keys being arranged to abut against the outer face of the outer guide roller support and the tapered front faces of said keys being arranged to engage the outer 10 ends of the elongated slots 39, 40, for forcing the two supports 1 and 2 snugly together as the keys are driven home.

To prevent the keys from dropping out and the bolts from being removed when the 15 outer support is detached from the inner support, I provide springs 43, 44, located in recesses 45, 46, surrounding the bolts 31, 32, which springs are interposed between the bottoms of said recesses and angular shoulders 20 47, 48, on said bolts.

The heads 33, 34, of the bolts are preferably made round so that the bolts may be turned into any position to bring their keys into different angular positions as shown in 25 dotted lines in Fig. 1.

To insure a perfect alinement of the axes of the two rollers when in operative position, the two supports are provided with an interlocking connection which is shown herein by 30 providing the adjacent faces of the two supports with horizontal tongues and grooves.

When it is desired to remove the drill steels, the keys may be released thus permitting the two supports to be separated by the 35 withdrawal of the heads of the bolts from their recesses and the disengagement of the tongue and groove connection between the adjacent faces of the two supports.

By providing the roller guide with a plain 40 inner roller and a flanged outer roller, it will be seen that the flanged outer roller may be removed with its support thus removing all restraint upon the drill steels in a lateral direction. This will permit the drill steels to 45 be removed without having to be swung over the flanges of the roller as would be the case if the inner roller were provided with the flanges instead of the outer roller.

It will be seen that the springs 43, 44, will 50 retain the keys within their elongated slots in the bolts when the outer support is detached from the inner support thus preventing the accidental loss of either the keys or the bolts from the said outer support.

55 It will furthermore be seen that ample provision is made for supplying oil to the rollers, in a very simple and effective manner.

It will also be seen that a very ready 60 means of permitting the roller axles to be removed when so desired, is also provided.

Certain of the parts shown and described 65 but not claimed herein form the subject matter of my application filed November 21, 1906, Serial No. 344460, entitled "Roller

guides for channeling machines," of which application the present application is a division.

What I claim is:—

1. In a roller guide for channeling machines, a guide roller and a support therefor having an oil chamber arranged to feed oil to the roller. 70

2. In a roller guide for channeling machines, an inner guide roller, a support therefor having an oil chamber arranged to feed oil to the said roller, an outer guide roller and a support therefor, having an oil chamber arranged to feed oil to the said roller. 75

3. In a roller guide for channeling machines, a guide roller and a support therefor having a plurality of oil chambers arranged to feed oil to the said roller. 80

4. In a roller guide for channeling machines, an inner guide roller, a support therefor having a plurality of oil chambers arranged to feed oil to the said roller, an outer guide roller and a support therefor having a plurality of oil chambers arranged to feed oil to the said roller. 85

5. In a roller guide for channeling machines, a guide roller, its axle and a support therefor having an oil chamber arranged to feed oil along the axle to the said roller. 90

6. In a roller guide for channeling machines, a guide roller, its axle and a support therefor having oil chambers at the ends of the axle arranged to feed oil along the axle to the said roller. 95

7. In a roller guide for channeling machines, a guide roller, its axle and a support therefor having an oil chamber at the end of the axle, said axle having an oil passage therein for feeding oil from the chamber to the roller. 100

8. In a roller guide for channeling machines, a guide roller, its axle, a support therefor having an oil chamber at the end of the axle, said axle having an oil passage therein for feeding oil from the chamber to the roller and an oil feeding wicking located in said chamber and passage. 105

9. In a roller guide for channeling machines, a guide roller, its axle and a support therefor having oil chambers at the ends of the axle, said axle having an oil passage therein for feeding oil from the said chambers to the roller. 115

10. In a roller guide for channeling machines, a guide roller, its axle, a support therefor having oil chambers at the ends of the axle, said axle having an oil passage therein for feeding oil from the said chambers to the roller and an oil feeding wicking located in said chambers and passage. 120

11. In a roller guide for channeling machines, guide rollers, their axles and supports therefor having oil chambers arranged to feed oil along the axles to the said rollers. 125

12. In a roller guide for channeling ma- 130

chines, guide rollers, their axles and supports therefor having oil chambers, said axles having oil passages arranged to feed oil from the said chambers to the said rollers.

5 13. In a roller guide for channeling machines, guide rollers, their axles, supports therefor having oil chambers, said axles having oil passages arranged to feed oil from the said chambers to the said rollers and oil feeding wicking located in said chambers and passages.

10 14. In a roller guide for channeling machines, a guide roller, a longitudinally removable axle therefor, its support, means for removably securing the axle to the support and a removable screw cap in the support in alinement with the axle.

15 15. In a roller guide for channeling machines, guide rollers, longitudinally removable axles therefor, their supports, means for removably securing the axles to the supports and removable screw caps in the supports in alinement with the said axles.

16. In a roller guide for channeling machines, a guide roller, a longitudinally removable axle therefor, its support having an oil chamber at the end of the axle arranged to feed oil along the axle to the said roller and a removable screw cap in the support in alinement with the said axle. 25

17. In a roller guide for channeling machines, guide rollers, their longitudinally removable axles, supports therefor having oil chambers at the ends of the axles arranged to feed oil along the axles to the said rollers and removable screw caps in the supports in alinement with the ends of the axles. 30

In testimony, that I claim the foregoing as my invention, I have signed my name in presence of two witnesses, this twenty-first 35 day of January, 1907.

WILLIAM PRELLWITZ.
